CURTAIN ROLL CUTTER

Gustaf E. Hubbard, Batavia, Ill.; Freda C. Hubbard executrix of said Gustaf E. Hubbard, deceased

Application February 4, 1937, Serial No. 124,152

2 Claims. (Cl. 143—86)

This invention relates to a curtain roll cutter, and more particularly to improved means for cutting such a roll so as to fit the previously measured window casing.

5 One feature of this invention is that it provides means for accurately determining the point at which said roll is to be cut; another feature of this invention is that it provides guide means at said point for a saw or other cutting tool; still 10 another feature of this invention is that it provides positive means for holding the curtain roll without danger of slippage or change of position when it is being cut; yet another feature of this invention is that it is adapted to receive all commercial sizes and diameters of curtain rolls; another feature is that two scales are provided, one for inside brackets and the other for outside brackets; a still further feature of this invention is that the device may be set directly at the measured width of the window casing, allowance being automatically made for the tips of each end of the roll and the necessary slack or play; other features and advantages of this invention will be apparent from the following specification and the 15 drawing, in which—

Fig. 1 is a side elevation of a device embodying this invention; Fig. 2 is a top plan view of the same device; Fig. 3 is a view of the slidable block along the line 3—3; and Fig. 4 is a view of the supporting and saw-guiding block, along the line 20 4—4 of Fig. 2.

The distance between opposite sides of window casings varies frequently, even between similar windows in the same room. In order to properly fit the roll supporting window shades or curtains to brackets mounted on such casings, therefore, it is necessary to measure the distance between each casing and to cut the curtain roll and curtain to fit that particular window. It has long 25 been customary in the trade to measure the casing width, make allowances for the tips and the necessary slack, mark a curtain roll by hand with a yardstick or tape, and then saw it by hand. Many errors occurred in this mode of operation, and it is not at all infrequent for 30% of the curtain rolls cut in this way to fit improperly. Sometimes they may be used even though they have 30 too much or too little slack, but frequently they are so far off as not to fit at all.

corresponding to the width of the window. It has mounted at one end of the scale a supporting block for the curtain roll, with a guide slot for a saw or the like at the point at which the curtain roll is to be cut, determined by placing one end of it against the block previously set to correspond to the window width. The device is so arranged that necessary allowances for the tips and for slack is automatically made for both inside and outside brackets.

In the particular embodiment of this invention illustrated herewith, an elongated base 10 of wood or similar material is here shown as of rectangular shape. The base has at one end thereof a supporting block 11 having therein a supporting slot 12 adapted to have a curtain roll lie therein and be longitudinally slidable therethrough when said roll is parallel to the long axis of the base. The block 11 has a second or guide slot 13 therethrough at right angles to the slot 12. This slot is so constructed and arranged to act as a guide for a saw for cutting the roll, or other instrument for marking it.

The base has slidably mounted thereon a block 14, which block is here shown as mounted by a bolt 15 projecting through a central longitudinal slot 16 in the base, provided at the upper end thereof above the block 14 with a wing nut 17 for manually locking the block at any desired point on the base. The block is also here shown with a spring 18 for frictionally retaining it while the wing nut is being tightened. It is to be understood, of course, that this spring is optional and that any convenient slidable mounting and locking means may be employed. In order to enable the block to slide readily along the base without the head of the bolt 15 striking a table or other place on which the base may be laid, blocks 19 and 20 are provided at the ends of the base to elevate it slightly above the surface on which it rests.

The base has graduated thereon the two scales 21 and 22, in linear units here shown as inches. While these scales are both graduated in the same units, it will be noted that they are not in registry with each other, nor do their zero points coincide exactly with the guide slot 13. The scale 21, intended for use where inside brackets are to be mounted on the window casing, has its zero

scale automatically compensates for the necessary allowance for the tip on the ends of the roll, and for slack or play. The scale 22 is designed for use where outside brackets are to be employed, 5 and its zero point lies $\frac{1}{16}$ " to the left of the guide slot 13. The two scales are thus displaced $\frac{1}{8}$ " with respect to each other, which has been found to be the correct differential between curtain rolls designed for inside and outside brackets. 10

10 Referring more particularly to Fig. 4, the supporting slot 12 in the block 11 is $1\frac{1}{4}$ " in width throughout a part or portion of the length, but has a reduced lower portion 23 one inch in width. The wider portion of the slot thus receives $1\frac{1}{4}$ " 15 rolls, while the reduced portion will receive and support $\frac{1}{2}$ inch or $\frac{3}{4}$ " rolls. The block 14 has mounted on the face thereof, directed toward the block 11, brackets 24 and 25. Both of these brackets are located in a position which corresponds 20 to the center of the supporting slot 12, but they are vertically displaced, the bracket 24 being at such a height as to coincide with the center of a roll supported in the wider portion of the slot 12; while the bracket 25, being somewhat lower, 25 coincides with the center of a smaller roll lying in the reduced portion 23.

Where it is desired to use this device to cut a curtain roll to fit a previously measured window casing, it is first determined whether inside or 30 outside brackets are to be used. The bracket edge of the block 14 is then set at a measured distance on the scale corresponding to the brackets to be used, and locked in place by tightening the wing nut 17. A curtain roll of the desired 35 diameter then has a tip placed on one end thereof, and the curtain roll locked in the slot 12 with the tip mounted in the bracket 24 or 25, depending upon the diameter of the roll. A saw is then inserted in the slot 13 and the roll cut, thus providing an accurately located squarely cut edge. 40 A cap and tip are then placed on this end of

the roll, and it is ready to be mounted on the window casing for which it was intended.

While I have shown and described certain embodiments of my invention, it is to be understood that it is capable of many modifications. 5 Changes, therefore, in the construction and arrangement may be made without departing from the spirit and scope of the invention as disclosed in the appended claims, in which it is my intention to claim all novelty inherent in my invention as broadly as permissible, in view of the prior art. 10

What I claim as new and desire to secure by Letters Patent is:

1. A device of the character described for determining a point at which a curtain roll is to be cut, including: an elongated base having two linear scales graduated thereon in the same units but about $\frac{1}{8}$ " out of registry with each other; a block on one end of said base having a supporting slot therethrough parallel to said scales and a guide slot therethrough perpendicular to said scales, said guide slot being located between the zero points of said scales, the distance between the zero points and said guide slot being adapted to compensate for inside and outside curtain roll brackets; a second block slidably mounted on said base adjacent said scales and adapted to be set at a predetermined desired graduation on either of said scales; means for locking said block at the point at which it is set; and means on said slideable block for supporting one end of said roll when said roll lies in said supporting slot. 20 25

2. Apparatus of the character claimed in claim 1, wherein said supporting slot has a portion of reduced width near the bottom thereof, and said slideable block has two supporting means thereon each of said supporting means being adapted to engage the tip mounted on a curtain roll. 30 40
